[57] **ABSTRACT**

An illustrative embodiment of the invention prevents strip work from "fluttering" and "canoeing" by establishing spaces of static high pressure fluid on both sides of the strip. Preferably, jets of pressurized fluid form the periphery of each of the static high pressure spaces. The jets and the static pressure thus formed, push the adjacent portion of the strip work back toward an equilibrium position with an increasing force as the strip comes closer to the jets in order to restore a well-balanced condition on both sides of the strip that eliminates fluttering and canoeing. This technique can be used in a cooling zone to heat treat the strip work, for example, in a continuous annealing furnace.

MEANS FOR PREVENTING THE FLUTTERING AND CANOEING OF STRIP WORK

DETAILED EXPLANATION ON THE INVENTION

The present invention relates to an improvement made in means for preventing the fluttering and canoeing of the strip work.

In a strip work processing line, or more particularly, a continuous annealing furnace for heat-treating strip work, the strip work goes through several serpentine movements in the furnace and further passes through a plurality of heat-treating zones that are varied in temperature. Consequently, the strip work is liable, because of the influence of the heat and also because of its intrinsic characteristics for rolling, to wave in direction normal to its surface, or in other words to flutter, and thereby to cause trouble in tracking and to unfavorably influence the heat treatment and the equipment used.

In order to prevent the fluttering of the strip work as described above, a mechanical means have been used in which several pairs of rolls are provided at various places in the furnace to hold the strip work from both sides, but this process is unsatisfactory because the surfaces of the strip work are liable to be damaged from contact with the rolls.

To overcome the aforesaid drawback, the present invention proposes an improved means to prevent strip fluttering without causing surface scratches by on its surface characterized in providing two lines of air chambers to face each other with the strip work travelling between them, the openings of each of said air chambers being disposed to face the surface of the strip work, each of such opening being divided by several partitions transverse to the direction of the strip work, and forming, when fluid pressure is supplied to the air respective chambers, to form a static pressure region in each partitioned opening between the strip work, the air chamber fluid being supplied in a jet from each partitioned opening.

BRIEF DESCRIPTION OF THE ATTACHED DRAWINGS

In the drawings showing a preferred embodiment of this invention,

FIG. 1 is a plan view showing a whole system including a partial section of the same,

FIG. 2 a front elevation view as seen from the line II - II of FIG. 1,

FIG. 3 a sideview of FIG. 2,

FIG. 4 an enlarged section of FIG. 3, and

FIG. 5 is a sketch cited for illustration.

Now, a preferred embodiment of this invention will be explained with reference to the attached drawings, in which 1 represents two lines of air chambers provided on both sides of the travelling strip work S and said air chamber 1 is divided into three spaces or volumes A, B, and C, by the partitions 2, 2 provided in direction normal to the surface of the strip work. The air chamber on the other side of the strip work has the structure, although not shown in the drawing, exactly the same as the other. Further, the hypothetic line S, in FIG. 1 shows the strip work travelling proximately and parallel to the air chamber 1, and the hypothetic line S_{II} in FIG. 1 indicates the strip work travelling in abnormal condition close to the air chamber 1. The air chamber

1, moreover, is provided with a convergent opening D, such opening being divided as described above into three distinct spaces, or rooms, A, B, and C by the partitions 2, 2, each of said spaces being further divided into small portions by the partitions 3, 3 provided in each spaces, forming as a whole a plurality of openings to oppose the surface of the strip work as seen in FIG. 2. The spaces, A, B, and C are designed, from the functional requirement, so that the spaces A and C are divided to be somewhat smaller in width, and the central spaces B is somewhat larger in width, and each of these spaces is connected with pipe 5 to supply fluid same in pressure and in flow rate.

Next, the guide pieces 6, 6 are provided respectively in said openings 4, 4 and serve to form peripheral passages for the fluid in the openings 4, 4. This fluid passage makes its way through all sides of the guide pieces 6, 6 . . . , because these guide pieces 6 6 . . . are installed in the air chamber, as shown in FIG. 4, by means of the beams 7, 7 with hollow space around it and further they are made smaller in size and convergent in shape like opening D. The guide piece 6 is attached in the air chamber 1 by fixing to the air chamber 1 the fixed piece 8 by bolt and such fixed piece 8 is welded to the beam fixed to the guide piece 6 by welding.

Because of the mechanism disclosed by this invention as described above, fluid under pressure is ejected from the opening 4 4 . . . passing through the passage around the guide piece 6, 6 . . . , when the fluid is supplied under same pressure and in same flow rate into the spaces, A, B, and C in the air chamber 1 through the pipes 5, 5 from the source (not shown in the drawing). When the strip work travels on the center line between the air chambers 1 and 1 as shown in FIG. 1, the strip receives same thrust by the pressure fluid ejected from the air chambers 1, 1 on both sides, and therefore the strip work travels in this state up and down unless the strip work is otherwise influenced. But, if the strip work travels closer to the air chamber on one side, as shown by the hypothetic line S_{II} of FIG. 1, the strip work receives on the side closer to the air chamber a greater thrust from pressure fluid jetted through the openings 4, 4 than the thrust it receives on the other side that is remote from the air chamber. The strip work in this manner is reverted to the center line where the thrust from both side becomes balanced. As stated in the foregoing, the strip work when coming closer to either air chamber is pushed back by the fluid pressure that is jetted from the opening 4, 4 and is enabled to travel always in a well-balance condition.

Owing to the mechanical structure as described in the foregoing, the strip work regulating means as disclosed in this invention is able to overcome the drawback commonly found in the conventional strip work regulating system as described in the following. In a case where the conventional system as shown in FIG. 5 is used, the pressure fluid flows, when the strip work comes close to the air chamber by a strong force due to some reason or other, in direction shown by the arrows in FIG. 5. The thrust works in direction normal to the strip, and because the pressure fluid flows up- and downwardly at an extremely high flow rate, the center F' of the opening becomes close to negative pressure. The strip work comes still closer, until at last the

strip work cannot be pushed back and, in the worst case, the strip work comes to contact the head of the opening.

However, in the strip work regulating means as disclosed by this the fluid ejected as shown by E of FIG. 4 is blown against the strip work by a given angle. Therefore the ejected fluid does not escape in upwardly or downwardly direction and is sure on impact to the strip work and to push it back. Particularly because the fluid is ejected through the passage around the guide piece 6 the center E' comes to form a space or room that is bounded by the air current characterizing the pressurized fluid the, strip work and the air chamber or the guide piece 6. In this instance, the space has a static pressure that helps to push back the strip work with increasing force as it draws closer to the guide piece 6. The angle of inclination of the passage for jetting fluid to be formed by the opening D is convergent in shape and the guide piece 6, is found by the experiment made by the present inventors preferably to be from 30° to 60°. Further, because the opening D is divided in transverse direction to the strip work, when a part of the strip work comes close to the opening as seen in the hypothetical line S II of FIG. 1, each opening 4 gives push back force corresponding to the distance to the strip work and can push back the strip work with good effect.

Furthermore, because the whole air chamber 1 in the strip work regulating system as disclosed by this invention is partitioned into several spaces, A, B, C, etc., when the strip work comes close as seen in the hypothetical line S II of FIG. 1, the pressure fluid jetted from the space at the right most end increases the transverse movement of the force to resist the strip work and the pressure within the space rises. Such increased pressure works to give thrust to the strip work without escaping into other spaces and thereby increasing the thrust by means of the partitioned spaces. Further, because the strip work often approaches to the opposite surfaces flat all over as shown by the hypothetical line S I of FIG. 1 or in a sloped state as shown by the hypothetical line S II of FIG. 1, the air chamber 1 should preferably be divided into the spaces in a manner in which the spaces at both ends are somewhat smaller in dimension than the one at the center in order to achieve a good functional result. This also holds true when dividing the spaces, A, B, and C further into smaller partitions.

Furthermore, this invention strip work regulating means can be used with good result also in a cooling zone when heat-treating the strip work in a continuous annealing furnace. Because the pressurized fluid is blown against the strip work from the openings as stated in the foregoing, the result of cooling can be further increased by using the cooling medium as the pressurized fluid. This invention system can serve the double purpose that is, cooling and the prevention of fluttering without providing any particular equipment in the cooling zone other than the cooling instrument.

Generally, the term "fluttering" means the waving of the strip work as seen in the hypothetical lines S, and S_{II} of FIG. 1. This invention system, however, shows a good result also in the prevention of the bowing or so-called canoeing of the strip work. Therefore, when used in this patent specification the term "fluttering" also is to be construed to include "canoeing" of the strip work.

Further, the present invention shall in no way be restricted by the example as described in the foregoing and various modifications within the scope as described in claim shall be included in this invention.

To summarize, the present invention proposes an improved strip material regulating system in which air chambers are provided in manner the travelling strip work can pass between them, each of said air chambers having openings disposed to face or oppose to the surface of the strip work, said opening being divided into several partitions in direct transverse to the strip work so that each of said partitions be given a static pressure zone formed by the fluid jetted from each partition, air chamber and the strip work when the pressure fluid is supplied into each air chamber and thereby the strip work go through heat-treatment without suffering any scratch from the fluttering to the great advantage to the industry.

I claim:

1. A device for preventing the fluttering of strip work which is directed along a path for treatment, comprising at least one housing defining a fluid chamber having a discharge adapted to be directed toward the strip work for positioning and treating the strip work, the discharge of the said fluid chamber comprising an opening elongated in the direction of the longitudinal axis of the strip work, a plurality of partitions extending transversely across said housing and dividing the discharge opening into several smaller openings, a guide piece positioned centrally within each smaller opening and leaving an annular peripheral slot between said guide piece and the respective adjacent ones of said partitions and defining an annular fluid jet discharge opening, and a fluid pressure pipe connection to said housing for supplying a constant pressure and flow fluid to said housing in the direction of said discharge opening, said housing having walls bounding said discharge opening extending substantially parallel to the axis of said fluid pressure pipe connection.

2. A device, according to claim 1, wherein at least one housing comprises two oppositely arranged housings between which the strip work is positioned, said guide pieces comprising rectangular members with side walls arranged in spaced parallel relation to said partitions.

3. A device, according to claim 1, wherein said housing includes a central large housing portion and an end housing portion on each side of said central housing portion, each having said partitions and each having a fluid pressure pipe connection.
